(57) **CLAIM**

The ornamental design for a hand crank radio, as shown and described.

DESCRIPTION

FIG. 1 is a front top left-side perspective view of the hand crank radio of the present invention;

FIG. 2 is a front bottom left-side perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is a back top perspective view thereof. The broken lines in FIG. 4 of the drawings define a boundary of the interior of holes extending into the hand crank radio that form no part of the claimed design thereof.
